UNITED STATES PATENT OFFICE.

JOSEPH BERGER, JR., OF UTICA, NEW YORK, ASSIGNOR TO UNION SPECIAL MACHINE COMPANY, OF CHICAGO, ILLINOIS, A CORPORATION OF ILLINOIS.

SEWING-MACHINE FOR COVERING SEAMS.

1,277,535.

Specification of Letters Patent.

Patented Sept. 3, 1918.

Application filed August 21, 1916. Serial No. 116,037.

To all whom it may concern:

Be it known that I, JOSEPH BERGER, Jr., a citizen of the United States, residing at Utica, in the county of Oneida, State of New York, have invented certain new and useful Improvements in Sewing-Machines for Covering Seams, of which the following is a description, reference being had to the accompanying drawing and to the figures of 10 reference marked thereon.

This invention relates generally to new and useful improvements in sewing machines, and more particularly to sewing machines of that type employed in covering 15 previously formed seams of various articles. It is herein shown as applied to a machine for covering knitted sweaters.

Heretofore, these seams have been covered by a two-needle machine which laid a 20 covering thread both above and below the seam. The resultant covered seam necessarily exposed one of said cross threads to view, and also both cross threads were insufficient to hold the shoulder seams against 25 stretching in a direction toward the shoulders.

One of the principal objects of this invention is, therefore, to provide a sewing machine having a pair of spaced needles and a 30 single looper coöperating therewith to lay a cross thread on the underside of the seam only, and to provide means for guiding a tape against the under face of the fabric whereby said tape will be stitched by both 35 needles and partially covered by the lower cross thread, thus avoiding any seam on the outside of the seam and serving to reinforce the underside of said seam by the tape whereby said seam will be prevented from 40 becoming stretched in a longitudinal direction as well as crosswise.

Another object of the invention is to provide a sewing machine having a differential feeding mechanism for gathering the knitted 45 fabric as it is fed to the stitching mechanism whereby said fabric will be prevented from becoming stretched during its passage through the stitching mechanism, and to provide a guide for directing the covering 50 tape from a point below the feeding mechanism and thence between the differential feeding dog to the main feeding dog whereby the differential feeding dog will only act on

the knitted fabric and thereby permit said differential feeding dog to perform its function. 55

These and other objects will in part be obvious and will in part be hereinafter more fully disclosed.

In the drawings, which show by way of 60 illustration one embodiment of my invention:

Figure 1 is a side elevation of a sewing machine embodying my invention, parts thereof being shown in section to clearly 65 disclose the feeding mechanism;

Fig. 2 is an enlarged detail view, parts thereof being shown in section to clearly 70 show the manner of directing the covering tape to the main feed dog;

Fig. 3 is a detail plan view of the work support showing the guide for the covering tape;

Fig. 4 is a detail front end elevation of the work support, showing the tape being 75 led upwardly therethrough;

Fig. 5 is a view showing the work support in cross section and the presser foot in elevation;

Fig. 6 is a detail top plan view showing 80 the relation between the main and differential feeding dogs and the looper; and

Fig. 7 is a detail bottom plan view of the completed article, the article and stitch being shown conventionally for convenience, 85 it being understood that the article is a knitted sweater and the stitch the Union Special twin needle stitch, well known in the art.

The invention is preferably applied to a 90 "feed-up-the arm" machine which comprises the usual cylindrical work support, an overhanging arm, a presser foot, a pair of spaced needles, a single threaded looper coöperating with both needles, and a differential feeding mechanism. The sweater sections, which have been previously seamed by a single line of through stitches, is opened out and fed through the stitching mechanism of the machine above described. A 100 covering tape is led upwardly through the end cap of the work support and thence upwardly between the differential and main feeding dogs so that the differential feeding dog will act directly on the knitted fabric 105 and gather the same in advance of the

needles, the main feeding dog engaging the tape and feeding the covered seam from under the presser foot.

Referring more in detail to the drawings:—

The sewing machine embodies the usual standard 5 the cylindrical work support 6 and overhanging arm 7. Mounted in the overhanging arm is a needle bar 8, carrying 10 a spaced pair of needles 9 and 10 respectively. This needle bar is reciprocated through the medium of a needle lever 11 which is pivoted on the overhanging arm at 12 and has connection with the needle bar by means of a link 13'. The needle lever 11 is oscillated by a pitman 12' coöperating with an eccentric on the main shaft 13, said shaft being journaled in the standard 5 and arranged in a plane at right angles 15 to the longitudinal axis of the work support 6. Also mounted in the overhanging arm 7 is the usual presser bar 14 which carries at its lower end the presser foot 15. Journaled in the work support 6 is a looper 20 rock shaft 16 and mounted upon this shaft is a thread carrying looper 17 which coöperates with both needles 9 and 10 to form what is generally known as a twin needle 25 stitch. The looper shaft 16 is oscillated in its bearings from the main shaft 13 to give 30 said looper its loop taking and loop shedding movements. This looper shaft is also given an endwise movement from the main shaft 13 so as to give to the looper its needle 35 avoiding movements. It will thus be seen that the looper 17 has the usual four-motions imparted thereto.

Also mounted in the work support 6 is a main feed bar 18 which carries a main feed 40 dog 19. Disposed between the feed bar 18 and the main shaft 13 is a train of mechanism which imparts to said feed dog the usual back and forth and up and down, or four-motion movements. Slidably mounted 45 in the main feed bar 18 is a differential feed bar 20, and this bar moves up and down in unison with the main feed bar 18 but is capable of having a differential movement thereto. Secured to the forward end 50 of the differential feed bar 20 is a differential feed dog 21 and disposed between the feed bar 20 and the main feed bar 18 is a train of mechanism for controlling the backward and forward movements of the 55 differential feed dog 21. By this train of mechanism, which includes a controlling lever 22, the feed dogs may move in unison or the differential feed dog 21 may have its feeding stroke of longer length than the 60 main feed dog so as to gather the knitted fabric in advance of the needles.

The above mentioned construction is shown and claimed in the pending application of James R. Moffatt, filed January 4, 65 1912, Serial No. 669,377, and I, therefore,

do not claim any of the above structure except in combination with my invention, as will be hereinafter described.

Secured to the front end of the work support 6 is a throat plate 23 which is provided 70 with the usual feed slots for receiving the main feed dog 19 and differential feed dog 21. This throat plate is provided with the usual needle openings for the needles 9 and 10. These needle openings are disposed at 75 a distance slightly in advance of the differential feed dog 21, and the throat plate in front of the needle openings is formed with an elongated guiding slot 24. The differential feed dog embodies three feed sections, 80 the outer sections 25 and 26 being longer than the intermediate section 27 so as to gather the knitted fabric and carry the same up to the needles, the intermediate section 27 being disposed in front of the slot 24 to assist in feeding the gathered material up to the tape which is fed upwardly through the slot 24. It will thus be seen that the guiding slot 24 for the tape is disposed between the main and differential 85 feed dogs. Detachably secured to the outer end of the work support 6 is the usual end cap 28 and the covering tape T is led through an inclined opening 29 at the lower corner of the end cap and thence upwardly 90 against the front face of said cap, thence through an opening 30 in the front wall of the end cap, and finally upwardly through the guiding slot 24.

In the operation of this machine, the previously seamed knitted sections S and S' are fed to the stitching mechanism, the edges thereof being disposed on the under side thereof so as to be covered by the tape. The seam of the garment is directed onto 100 the tape so that the needles will enter the sections of the garment on either side of the previously formed seam and also enter the tape. The looper thread which coöperates with the two needle threads will lay a cross 105 thread against the under side of said tape. By leading the tape upwardly between the main and differential feed dogs, the differential dog will not engage the tape but will engage the knitted fabric and cause the latter to be sufficiently gathered to prevent any undue stretching thereof while the article is being fed from under the presser foot by the main feed dog.

It will also be noted that by applying the 110 tape to the under side of the shoulder seams of sweaters, the tape will prevent any longitudinal or transverse stretching of the seam, and at the same time, cover the previously formed seam; and that by omitting 115 the upper cross thread the garment thus formed will not disclose any covering threads on the outside thereof.

It is obvious that minor changes in the details of construction and the arrangement 120

of parts may be made without departing from the spirit of this invention, as set forth in the appended claims.

Having thus described my invention, what 5 I claim as new and desire to secure by Letters-Patent is:—

1. A sewing machine including in combination stitch forming mechanism having spaced needles, means for guiding the previously 10 joined edges of fabric sections centrally between said needles and means for guiding a tape to the stitch forming mechanism from a point below the guiding means and between the guiding means and the needles, whereby said tape is joined by the 15 needles to the fabric sections and covers the under face of the joined edges.
2. A sewing machine including stitch forming mechanism and differential feeding mechanism, and means for guiding a tape to the stitch forming mechanism from a point below the feeding mechanism between the elements of the differential feeding mechanism, the differential element of the feeding 25 mechanism operating upon the body fabric only and the main feed element of the differential feeding mechanism operating upon the body fabric and the tape after the latter is stitched to the body fabric.
3. In a sewing machine, stitch forming mechanism including spaced needles and an under concatenating thread laying mechanism, a feeding mechanism including a main feed dog and a differential feed dog, the latter being located in advance of the needles, and means for guiding a tape to the stitch forming mechanism between the differential and main feed dogs whereby the body fabric 35 may be gathered in advance of the needles and the tape stitched to the fabric.
4. In a sewing machine, stitch forming mechanism including spaced needles and an under cross thread laying mechanism, a feeding mechanism including a main feed dog and a differential feed dog, the latter being located in advance of the needles, and means for guiding a tape to the stitch forming mechanism between the differential and main feed dogs whereby the body fabric 45 may be gathered in advance of the needles and the tape held and covered by the under cross thread laying mechanism.
5. A sewing machine including a longi-
- tudinal work support, stitch forming mechanism comprising spaced needles and an under thread concatenating mechanism, a feeding mechanism working longitudinally of the work support and including differential and main feed dogs, and means for guiding a tape from below the needle mechanism between the differential feed dog and the main feed dog, the differential feed dog being arranged to act only on a body fabric and the main feed dog upon the stitched and taped fabric, the tape being covered by the under concatenating thread.
6. A sewing machine including a longitudinal work support, stitch forming mechanism comprising a pair of spaced needles and a single lower cross thread laying mechanism, a feeding mechanism working longitudinally of the work support and including differential and main feed dogs, and means for guiding a tape from below the feeding mechanism between the differential and the main feed dogs, whereby the differential feed dog will act only on the body fabric being stitched, and the main feed dog upon the stitched and taped fabric, and the lower thread will cover the tape.
7. In a machine of the character described, the combination with spaced needles and under thread concatenating mechanism, main and differential feed dogs, a throat plate having needle and feed dog slots and having a transverse slot located in advance of the needle openings and in rear of the differential feed dog slots whereby a tape may be guided from below through the throat plate to the stitch forming mechanism.
8. In a machine of the character described, a work support, an end cap mounted thereon and provided with guiding slots, a differential feeding mechanism including differential and main feed dogs, said guiding slots in the end cap being arranged to guide a tape from below the feeding mechanism upwardly between the feed dogs.

In testimony whereof I affix my signature 100 in the presence of two witnesses.
